UNITED STATES PATENT OFFICE.

JOSEPH ABRAMS, OF STURGIS, SOUTH DAKOTA.

ARTIFICIAL-LIMB SOCKET.

1,398,824.

Specification of Letters Patent. Patented Nov. 29, 1921.

Application filed March 1, 1921, Serial No. 448,745. Renewed October 20, 1921. Serial No. 509,204.

To all whom it may concern:

Be it known that I, JOSEPH ABRAMS, a citizen of the United States, residing at Sturgis, in the county of Meade and State of

5 South Dakota, have invented certain new and useful Improvements in an Artificial-Limb Socket, of which the following is a specification.

This invention relates to improvements in 10 artificial limbs, and more particularly to a limb stump receiving socket therefor.

The principal object of the invention is to provide for an improved limb stump socket for artificial limbs, and one embodying a rigid socket member adapted to be removably supported in the upper open end of an artificial limb, a cushioning limb stump receiving member or pocket capable of being independently removed from position within 20 the rigid socket, and means whereby the cushioning member or socket may be inflated or deflated to any desired or necessary degree to render the socket comfortable to the wearer, or to compensate for limb stump shrinkage without the removal of the rigid socket from the artificial limb, the cushioning member or socket from the rigid socket, or the limb stump from the latter.

With the foregoing and other objects in 30 view, the invention resides in the certain new and useful construction and arrangement of parts, as will be hereinafter more fully described, set forth in the appended claims, and illustrated in the accompanying drawings, in which:—

Figure 1 is a fragmentary elevation of the upper portion of an artificial limb showing the preferred form of the improved limb stump socket positioned therein, the wall of 40 the artificial limb and the socket member being broken away to show the parts positioned for the inflation of the cushioning socket without the parts of the socket being separated entirely from the artificial limb, 45 and,

Fig. 2 is a vertical transverse section of the removable limb stump socket and the cushioning means thereof.

Referring to the drawings, wherein similar characters of reference designate corresponding parts in the several views thereof, the numeral 10 indicates the upper open ended portion of an artificial limb which may be of any usual or known construction 55 suitable to receive in its open end a substantially rigid socket member 11, formed pref-

erably of an annular ring of rawhide, and in the nature of a cylindrical sleeve, and which is to be held in place by any suitable means (not shown).

Fitted into the socket member or sleeve 11 is an annular cushioning means or member 12, preferably formed of a tubular rubber or rubberized fabric, which is adapted to be held in position within a pocket formed 65 of a piece of fabric, preferably of chamois skin, or the like, which has a lower intermediate portion 13 secured by a circular line of stitching 14 inwardly from the bottom edge of the socket or sleeve 11, and its upper intermediate portion, as at 15, trained over the top edge of the latter and folded upon itself, as at 16, exteriorly thereof, a line of stitching 17 holding the same in folded condition and passing through the 70 wall of the socket or sleeve 11, and securing the fabric pocket against the upper inner surface of the latter. The upper free edge portion of this fabric is turned inward of the open end of the socket or sleeve 11 and 80 passes centrally therethrough and through the center opening of the cushioning socket or member 12 to a point inward of the lower edge of the latter, where it is connected to the lower free edge 19 of the pocket fabric 85 by means of the draw-string 20. The pocket thus formed securely retains the cushioning socket or member 12 in desired position, but allows for the same to be inflated to a desired limited degree, which degree may be 90 varied throughout a wide range by simply loosening or tightening up of the draw-string 20.

It is to be particularly noted of the specific arrangement and manner of securing 95 the pocket fabric to the rigid socket or sleeve 12, that the lower edge portion 19 thereof is drawn upward from the lower edge of the sleeve whereby to support the lower edge of the cushioning member or socket 12 inward 100 of the lower end of the same, and to force the top edge of the latter upward into or slightly above the plane of the top edge of said rigid socket. This slight upward extension of the top edge of the cushioning 105 member or socket 12 is permitted by reason of the pocket fabric being folded and secured exteriorly to the upper portion of the outer wall of the rigid socket 11, and such extension forms one of the salient features 110 of the present invention, inasmuch as it provides for the interposing of the upper por-

tion of the cushion between the limb stump inserted through the same and in hard top edge of the said rigid socket. Secured by the 5 upper line of stitching 17 exteriorly of the rigid socket 11, is the outer end edge of a usual form of soft leather cuff or sleeve 21, which is adapted to be turned inwardly of the upper open end of the rigid socket 11 and passed downwardly of the center opening 10 of the cushioning socket.

For the purpose of inflating the cushioning member or socket 12, a radially extending flexible tube 22 is formed with or otherwise attached thereto, and is provided at its 15 outer end with a removable cap 22', inclosing an inflation valve (not shown) of any usual or desired form.

In the use of the device thus provided, the parts thereof are assembled as by the 20 cushioning socket 12 being placed in position within the pocket, with the tube 22 projecting outwardly through an opening formed in the wall of the latter and the wall of the rigid socket, and the flaps 18 and 19 of the pocket then drawn together and secured by means of the drawing string 20. The 25 rigid socket 11 is now ready to be inserted into the open end of an artificial limb 10, or otherwise secured in position thereon. When 30 the assembled socket is inserted within the open end of the artificial limb 10, the valve tube 22 is in extended position radially thereof and is flexed or bent in an upward direction when contacted by the upward 35 movement of the wall of the upper end or edge of the socket portion of the artificial limb with respect thereto, in which flexed or bent position the tube 22 is retained partly in a groove or recess 23 formed in the outer 40 wall of the rigid socket or member 11, and partly in a vertically disposed slot 24, formed in the wall of the upper portion or integral socket of the artificial limb 10, the latter being normally closed by means of a suitable 45 closure 25, which may be movably supported in proper position on the outer face of the limb socket 10, as by a pivotal connection 26.

The artificial limb 10, as a whole, is now ready to be engaged onto the limb stump of 50 the person to wear the same. Should it be necessary to further inflate the cushioning socket 12, as for the purpose of making the socket as a whole more comfortable, or to compensate for the shrinkage of the limb, 55 such inflation can be done without removing the stump socket from its position on the artificial limb or without removing the limb stump from the same, simply by withdrawing the closure 25 from over the slot 24 to 60 allow the tube 22 to spring outwardly therethrough and from the groove or recess 23, and attaching thereto a pump or other inflation means to be used for the purpose, after

which, the pump or inflation means is detached and the tube 22 is pushed inward of 65 the slot and secured in normal position therein by returning the closure 25 to its position over the slot.

From the foregoing it will be readily apparent that this invention provides for an 70 extremely simplified limb stump socket capable of quick adjustment into operative position on artificial limbs; that it provides for the effective cushioning of the limb 75 stump within the socket and particularly in a manner to prevent injury to the limb at the top edge of the socket; and that it provides for a cushioning socket capable of being inflated or deflated, as the case may be, to properly adjust the same for the comfortable 80 engagement and support of the limb stump, and for suitably compensating, by inflation to different degrees, for shrinkage of the limb stump which takes place during a 85 comparatively long period of time after the loss of the natural limb from the stump, such inflation or deflation being permitted without the necessity of removal of the limb 90 stump from the socket, or the socket from the artificial limb.

It is to be understood that the invention 95 contemplates the making of the limb stump sockets in various sizes, each with a cushioning member or socket capable of being inflated throughout a sufficient range for the purpose of compensating for the 100 stump shrinkage, and that various changes in detail of construction and arrangement of the parts may be resorted to without departing from the spirit and scope of the same.

Having thus fully described the invention, what is claimed, is:—

The combination with the upper open end portion of an artificial limb, of a rigid socket member adapted to be supported in the open 105 end thereof, an annular inflatable cushioning socket within said rigid socket, a valved inflating tube leading radially from said cushioning socket and extending outwardly of an opening formed in the wall of said 110 rigid socket, said inflating tube being normally disposed in inoperative position partly within a vertically elongated recess formed in the outer wall of said rigid socket and partly in a slot formed in the wall of the 115 open end portion of the artificial limb, and a closure movably mounted on the outer face of the wall of the open end of the artificial limb and adapted to cover the said slot, said inflating valve being adapted to spring outwardly from the said recess and slot when said closure is moved from over the slot for such purpose.

In testimony whereof, I affix my signature hereto.

JOSEPH ABRAMS.
